UNITED STATES PATENT OFFICE

HAROLD W. A. DIXON, OF HOLLIS, NEW YORK, ASSIGNOR TO COLUMBIA RIBBON & CARBON MANUFACTURING COMPANY, INC., OF NEW YORK, N. Y., A CORPORATION OF NEW YORK

PROCESS OF MARKING PAPER

Application filed May 7, 1927. Serial No. 189,747.

My invention relates to an improved process for the marking of papers, such as carbon papers.

In the manufacture of such papers, a supporting tissue or thin paper is coated on one side with carbon ink, this ink being absorbed to a certain extent by the supporting tissue, so that the back thereof is darkened, to a degree dependent upon the absorptive properties and the weight or thickness of the paper. It is an object of my invention to apply a marking to such paper by varying the amount of carbon ink which is absorbed by the supporting tissue, so that the back of 10 the sheet will present a mark, due to the variation in the ink absorbed, contrasting in appearance with the rest of the sheet. The process by which the desired results are obtained is, I believe, superior to the processes 15 or methods of marking now employed.

Prior to my invention, manifolding or carbon papers have been marked by applying printing ink thereto, both before and after the carbon ink has been applied, the 20 visibility of the applied design or marking being obtained by the pigment used in the ink employed for printing the design or mark.

Another method employed previously is 25 the application to the supporting paper or tissue of a more or less colorless printing material, such as printer's varnish, in the form of the desired design or mark, this varnish rendering the area of the supporting tissue to which the same is applied impervious to the carbon ink, the printed surface or varnished surface therefore presenting a different appearance from the remainder of the sheet.

40 In the practice of my invention, instead of applying the marking or design with printer's ink and relying upon the pigment in the printer's ink for visibility, or instead of employing a printer's varnish or similar material which renders the paper or tissue impervious to the carbon ink, I do not change the permeability of the paper, but lessen the 45 penetrating qualities of the carbon ink at the mark-receiving portion of the paper or tissue, so that the amount of ink which pene-

trates to the back of the supporting tissue or paper will be less than that penetrating the remainder of the paper, thereby to provide a design or mark greatly contrasting in appearance with the remainder of the paper or tissue into which the ink has penetrated.

To lessen the penetrative qualities of the carbon ink, I apply the desired design to the paper or tissue, with an alkali solution, such as a solution of ethyl or methyl, alcohol and 50 caustic soda or potash, and when the carbon ink is applied to the tissue or paper so treated the penetrating qualities of the ink will be reduced at the mark-receiving portion of the paper or tissue, due to the saponifying action of the alkali solution upon the ink. As 55 a result, that portion of the paper to which the solution has been applied in the form of a design or mark will contrast in appearance with the remainder of the sheet.

In both cases, therefore, without changing the permeability of the supporting paper or tissue—in fact, without changing the character of this supporting paper or tissue at all—I effect a change in the penetrating qualities 75 of the carbon ink so as to produce on the finished sheet or surface a mark or design contrasting in appearance to the remainder of the sheet.

The material employed for lessening the 80 penetrating qualities of the carbon ink may be applied on either or both sides of the uncoated supporting paper or tissue with equal effect, and the alkali solution may be applied either before or after the application of the ink, although a more pronounced effect is produced if applied prior to the application 85 of the ink.

In the manufacture of carbon papers as 90 now practised it is quite usual to employ a supporting tissue or paper which has been colored by the paper manufacturer before the carbon ink is applied thereto. I find with such papers that upon the application of the alkali solution not only are the penetrating 95 qualities of the ink altered, but the solution bleaches the dye employed in dyeing the original tissue, with the result that I obtain a mark or design on the finished sheet which perhaps is even more contrasting in appear- 100

ance than where a white paper is employed for the supporting tissue.

In the accompanying drawings, Fig. 1 shows in perspective the first step in the process of marking paper by my improved method; and Fig. 2 is a similar view showing the finished sheet.

Referring to the drawings in detail, 1 designates a sheet of paper which is to be converted into carbon paper and to have a mark applied thereto. The mark, which is shown at 2, is applied to the sheet 1 before the sheet has had its ink applied thereto by applying the desired mark or design with an alkali solution such as a solution of ethyl alcohol and caustic soda or potash. As above noted this material has the property of lessening the penetrative qualities of the carbon ink and consequently when the paper 1 receives its coating 3 of carbon ink which it will be understood is applied to the entire surface of the sheet the presence of the alkali solution on the paper sheet reduces the penetrative qualities of the ink where the mark or design is applied with the result, as will be appreciated, that the mark will appear in the finished sheet in a lighter shade than the main portion body or ground of the sheet.

While I have mentioned certain materials as being suitable for use in the practice of my invention, it is to be understood that these examples are illustrative and not definitive and that my invention comprehends the employment of any suitable material which will lessen the penetrative qualities of the ink at the portion or area of the supporting paper or tissue at which the contrasting design is to appear. I wish it to be understood that the expressions "carbon ink" and "carbon paper" are to be interpreted in their generic sense. I wish it to be understood also that my process is not necessarily limited to applying a mark or design to a mere limited area of the sheet, but may be applied to the entire sheet, practically, in any desired design.

What I claim is:

1. The process of marking carbon paper, which process consists in applying the desired mark to the supporting paper or tissue in an alkali solution and thereafter coating the supporting paper or tissue with carbon ink.

2. The process of marking carbon paper, which process consists in applying the desired mark to a supporting paper or tissue in a material capable of saponifying the carbon ink at the mark-receiving portion of the paper or tissue, and thereafter coating said paper or tissue with carbon ink.

3. In the process of marking carbon paper in which the carbon ink is supported or carried by a colored paper or tissue, the step which consists in applying the mark to the mark-receiving portion of the supporting

paper or tissue in a material which will chemically change the color of the said paper or tissue.

4. In the process of marking carbon paper in which the carbon ink is supported or carried by a colored paper or tissue, the step which consists in applying the mark to the mark-receiving portion of the supporting paper in a material capable of chemically changing the color of the paper and chemically affecting the penetrating qualities of the carbon ink.

This specification signed this 5th day of May, 1927.
